HELMET

Archibald J. Turner and John G. Havey, Chicago,
Ill., assignors to Wilson Athletic Goods Mfg.
Co., Inc., Chicago, Ill., a corporation of Dela-
ware

Application March 11, 1950, Serial No. 149,172

5 Claims. (Cl. 2-3)

1

Our invention concerns helmets and more particularly helmets especially suitable for wear in playing football and other comparably rough games.

A salient object and accomplishment of our invention is the provision of a helmet that itself absorbs a substantial portion of the shock energy of any sharp or heavy blow sustained thereby and then relatively very slowly distributes the remainder of that shock energy over a large area of the head of the wearer.

By virtue of our just mentioned accomplishment we are enabled to avoid or effectively minimize head jolts. A head jolt properly may be defined as a sudden and/or severe change in the direction in which the head is moving, or the velocity with which it is moving, or both. The avoidance of sharp and/or severe head jolts is of vital importance. The human brain "floats" in the skull much as the yolk of an egg has floating suspension in its associated egg white. A sharp or severe jolt can rupture an egg yolk without fracturing the egg shell. Similarly, a sharp or severe jolt can cause fatal injury to a human brain without fracturing the skull which houses it—and often with only minor, if any, evidence of injury at the outside of the head. There have been many such fatal head injuries in the playing of football.

Tape or strap suspensions, with which most modern game helmets are provided, have been sadly inadequate to the avoidance of severe head jolts. In their functioning to prevent or minimize external head injuries, they all too often are the contributing causes of much more serious internal head injuries.

With the above discussed matters in mind, we have realized that the components of a football or like helmet should be so constructed and arranged, and be formed of such materials, that they actually absorb a substantial, preferably major, portion of the shock energy of any blow sustained by the helmet and then transmit the remainder of that shock energy to the head during a significant time interval, i. e., relatively slowly, and preferably over the largest possible area of the head.

In the case of a player wearing the helmet of our present invention, and even though his head remains substantially stationary pursuant to a blow sustained by the helmet, the slow rate of speed at which shock energy is transmitted to the head by and through the helmet components affords the player an advantage comparable with that "rolling of the head with the blow" which is of paramount importance in boxing.

Another object of our invention is the provision of a game helmet that is sufficiently hard, where it should be hard, to afford optimum protection, yet resilient and flexible enough to absorb shock energy; a helmet that adequately protects its

2

wearer but will not serve as a lethal weapon against an opponent or teammate.

Other objects of our invention are to improve the shape, and the constituent material, and the performance under shock, and incidentally the appearance, of the shell element of a game helmet.

Another object of our invention is to provide a game helmet that may and does comprise a strong, tough, flexible, light weight, molded, shell element that retains its toughness and flexibility at low temperatures and may and does present only smooth and convexly curved exterior surface.

Another object of our invention is to provide a game helmet which will serve very satisfactorily without (although it may be provided with) the conventional chin strap.

Another object of our invention is to provide a game helmet that is provided with novel, soft, light-weight, and effective composite padding comprising in its construction two characteristically different species of soft rubber, or rubber-like material, which function differently but conjointly in the realization of that salient object of our invention which is stated in the second paragraph of this specification.

Another object of our invention is to provide composite padding of the kind aforementioned which comprises, inter alia, an elongated unit simultaneously engageable with the forehead and head crown and the skull base of the wearer, having some or all of these advantages:

(a) It is easily ventilated and cleaned.

(b) Although readily pullable away from the inner surface of the helmet shell and to a position largely outside of the latter for cleaning, ventilation, inspection or repair, it automatically assumes and maintains a position closely adjacent and conforming to the opposed inner surface of the shell when pressed back into the shell.

(c) It lends itself to simple paring operations that will adapt the helmet to any one of several head sizes.

Yet another object of our invention is to provide composite padding of the kind aforementioned which effectively protects the ears and sides of the head of the helmet wearer and which, as installed in the helmet, is readily manipulable for cleaning, inspection, or repair.

The aforementioned and other features, objects and advantages of our invention will appear from the following detailed description wherein reference is made to the accompanying three sheets of drawings in which:

Fig. 1 is a front elevational view of a helmet embodying our invention;

Fig. 2 is a side elevational view thereof;

Fig. 3 is a rear elevational view thereof;

Fig. 4 is a bottom plan view revealing the interior of the helmet;

Fig. 5 is a vertical sectional view, on somewhat

larger scale than the preceding figures, which may be regarded as taken in the plane of the line 5—5 of Fig. 1 and looking in the direction indicated by the arrows;

Fig. 6 is a sectional view, in an upright but not exactly vertical plane, which may be regarded as taken in the plane of the line 6—6 of Fig. 2 and looking in the direction indicated by the arrows;

Fig. 7 is a sectional view, generally similar to Fig. 5, depicting how the illustrated parts of the helmet appear when, for the purpose of cleaning or ventilation or inspection or repair, there is pulled from the helmet that elongated composite pad member which is adapted simultaneously to engage the forehead and the head crown and the skull base of the helmet wearer;

Fig. 8 is an isolated plan view of the aforementioned elongated composite pad member; and

Fig. 9 is a view of one of the ear and head side protecting composite pads as it would appear if removed from the helmet and looked at from the face thereof which normally lies adjacent to the inner surface of the helmet shell.

Similar numerals of reference refer to similar parts throughout the several views.

The helmet shell, depicted at 10, preferably is formed of a composition that, essentially, is an appropriately proportioned mixture of rubber and a moldable plastic resin. The plastic resin accords firmness and a requisite degree of hardness to such composition; the rubber accords it toughness and flexibility and resiliency, and additionally freedom from brittleness down to temperatures as low as 0° Fahrenheit. Shell 10 is molded in one piece and is practically indestructible. All portions of its exterior are desirably smooth. An incidental purpose of such smoothness is to afford the helmet a pleasing appearance, but the principal purpose of such smoothness is to dispense with all surface projections which might be the receivers of glancing blows in play tending to turn the helmet on or with the head of the wearer, or which in play might cause lacerations or abrasions of the face or other surface parts of the body of an opponent or teammate.

Shell 10 is sufficiently large and of such shape, as illustrated, that the complete helmet of which it forms a part will receive and extend down on the head of the wearer to protect both his forehead and the base of his skull as well as the crown of his head and his ears and the sides of his head. The shell shape depicted in the drawings does not interfere with the vision, or freedom of head movement, of the wearer of the completed helmet whereof the shell forms a part although such helmet affords an optimum maximum of protection to his head.

The plastic resin ingredient of the composition of shell 10 desirably is a copolymer of about 11% butadiene and about 89% styrene. Preferably it is the Pliolite S-6 resin produced and marketed by Goodyear Tire & Rubber Company of Akron, Ohio. The rubber ingredient of such compound desirably is a synthetic rubber in the nature of a copolymer of 25% to 30% styrene and 75% to 70% butadiene—a soft material that closely resembles natural rubber. Desirably such rubber ingredient is the GR-S rubber produced and marketed by the Office of Rubber Reserve, Reconstruction Finance Corporation.

The shell composition should comprise from 70 parts down to 40 parts of the aforementioned plastic resin and from 30 to 60 parts of the afore-

mentioned synthetic rubber, with the sum of the number of parts of the plastic resin and the number of parts of the synthetic rubber desirably being 100. These materials suitably are mixed together, with the aid of a standard rubber mill in accordance with conventional rubber milling techniques. No equipment other than that normally available in rubber factories is necessary to the mixing of such materials.

In completing the compound from which the shell 10 is molded, the above discussed mixture of the plastic resin and the synthetic rubber has added thereto and thoroughly commingled therewith suitable conventional rubber compounding ingredients that are necessary or desirable to the end that the shell may vulcanize when molded at a temperature of about 320° F. for a period of about fifteen minutes. A formula for the compound used in molding the shell 10 which we have found to be quite satisfactory for our purpose (although none of the percentages is critical and even the presence of some of the ingredients is optional) is as follows:

Ingredient:	Parts by weight
The plastic resin (desirably Pliolite S-6)	70.0
The synthetic rubber (desirably GR-S)	30.0
Stearic acid	2.0
Silene EF	30.0
Zinc oxide	5.0
Age-Rite-White	2.0
Altax	1.5
Tuads	0.2
Sulphur	2.0

Shell 10 desirably is provided with a plurality of rows of ventilating openings 11, with such openings aligned with the elongated slots in the hereinafter discussed composite padding member which simultaneously engages the forehead, crown of the head, and base of the skull, of the helmet wearer. The portions of the shell which are intended to lie opposite the sides of the helmet wearer's head are externally bulged at 12 to provide complementary internal recesses or pockets which accommodate the two lateral composite padding elements presently to be mentioned. Each bulge 12 desirably is provided with at least one ventilating opening 13.

Indicated as a whole by reference numeral 14 is the composite padding member, engageable simultaneously with the forehead and crown of the head and base of the skull of the wearer, to which we have previously alluded. It is laminated. It consists of elongated rectangular soft rubber laminae 15 and 16 of equal widths and having aligned longitudinal edges, the lamina 15 suitably being somewhat longer than lamina 16 and the latter suitably having a beveled end edge 17 which lies somewhat short of the corresponding end edge of lamina 15 (see Figs. 7 and 8). The opposed faces of the soft rubber laminae 15 and 16 are adhered each to the other, as by cementing or vulcanization, and each of such laminae is provided with a plurality of elongated through slots 18 each registering with the corresponding slot of the other lamina. Such through slots 18 are suitably disposed in three ranks, and two files extending lengthwise of composite padding member 14.

While the laminae 15 and 16 of the composite padding member 14 are both of relatively soft rubber, they are formed of different kinds of soft rubber, and such difference in kind is of paramount importance in the functioning of our new helmet. Lamina 16 is formed of latex foam rub-

ber that is porous and sponge-like in that its pores will breathe out air when the rubber is compressed and breathe in air when the rubber is released from compression. Lamina 15, however, is formed of that now well known cellular soft rubber in which a gas, suitably nitrogen, is permanently entrapped in a great multitude or veritable myriad of closed cells occurring throughout the rubber structure. No compressive stress sustained by this kind of cellular soft rubber will expel its entrapped quanta of gas—it will not completely flatten under any compressive force exerted upon it.

While we do not limit ourselves to any particular thicknesses for the soft rubber laminae 15 and 16, we suggest that in a football helmet the minimum thickness of the composite padding member 14 be not less than half an inch and that its thickness at most points be as much as three quarters of an inch.

Desirably the composite soft rubber padding member 14 is mounted in the shell 10, and shielded from direct contact with the head of the helmet wearer, by a strap-like element 19 of sufficiently strong soft pliable leather which is somewhat longer than the soft rubber lamina 15. Leather element 19 is cemented, or otherwise suitably adhered, to the proximate face of rubber lamina 15, and has its lateral edges turned against and adhered to the lateral edges of lamina 15. It has elongated through slots 20 in registry with the through slots 18 of the laminae 15 and 16. It is a very desirable component of the composite padding member 14. One end of the element 19 extends beyond the adjacent end of the lamina 15 and suitably has an inturned end edge exteriorly secured at 21 to the forehead edge of shell 10 by stitching 22. The other end of the element 19, and the rubber which it embraces, are conformed to provide a leather-faced protecting bead 23 for the base of the skull (nape of the neck) of the helmet wearer. Such bead 23 is retained as such, and is secured to the contiguous intermediate portion of the lower edge of shell 10, as by stitching 24.

Disposed on opposite sides of the just discussed composite soft rubber padding member 14 are other composite soft rubber padding members, each of which is designated as a whole by reference numeral 25. Each composite padding element 25 comprises a centrally apertured plate 26 of the latex foam (sponge-like) rubber to which we have previously alluded, a curvate bar 27 and an ovate plate 28 both formed of the gas entrapping cellular rubber to which we have previously alluded, and a soft leather facing 29.

Curvate rubber bar 27 lies against and is cemented or otherwise adhered to the rubber plate 26 at the upper and rear margins of the face thereof that is presented to shell 10. The ends of curvate bar 27, and the edge thereof which lies away from the proximate edge of rubber plate 26, are preferably tapered as indicated at 30 (see Figs. 6 and 9).

The inner edge of rubber plate 26 also is suitably tapered as indicated at 31. The ovate rubber plate 28 overlaps such tapered edge 31, and is cemented or otherwise adhered to that face of rubber plate 26 which is presented to shell 10.

Ovate plate 28 is provided with a through aperture 32 which lies opposite one of the shell side apertures 13 and is in registry with a through aperture 33 in the leather facing 29.

The leather facing 29 of each of the shell side padding members 25 is cemented or otherwise ad-

hered to the contiguous face of its associated rubber plate 26, and is turned alongside of and adhered to the upper and rear edges of such plate 26 and the contiguous edge of the curvate bar 27, and is conformed to sheath a rubber bead 34 which extends along and interiorly of the adjacent front and lower side edges of the shell and is there retained by stitching 29.

Rivets 36, which extend through each facing 29 and its associated ovate rubber plate 28, secure those parts to the adjacent inner face of shell 10, and supplement the stitching 35 in retaining the composite padding elements 25 to the shell. The upper and rear edges of each composite padding member 25 normally are pressed against the inner side faces of shell 10 by the resiliency of the rubber of those padding members.

Indicated at 37 by dotted lines in Figs. 1, 2, 3, 4 and 7 is a conventional chin strap with which our helmet may be equipped, if desired, and at 38 are indicated snap fastener studs, carried by the shell 10, by which the attachment of such a chin strap to the helmet may be effected. However, our helmet requires no chin strap, and ordinarily we prefer that no chin strap be provided. The fastener studs are dispensed with when the use of a chin strap is not contemplated.

A helmet characterized by the features of novelty which we now have illustrated and described has important practical advantages to which we shall make brief reference. The foam latex components of the composite padding elements 14 and 25—25, being very soft, enable the helmet to conform itself snugly to, and follow any peculiar contours of, the head of the helmet wearer.

When a player equipped with one of our new helmets sustains a severe head blow, the shell 10 and the composite rubber padding elements 14 and 25—25 effectively cooperate to protect such player by themselves absorbing a substantial portion of the shock energy of the blow and then relatively very slowly distributing the remainder of that shock energy over a relatively large area of the player's head. The shell 10, by reason of its special composition, momentarily distorts to absorb much of such shock energy, at least one (but ordinarily more than one) of the latex foam rubber components of the composite padding elements 14 and 25—25 quickly and more or less completely compresses and breathes out air whilst absorbing an additional portion of such shock energy, and at least one (but ordinarily more than one) of the gas-entrapping cellular rubber components of such padding elements, which was only partially compressed without loss of gas during the distortion of the shell 10 and the compression of at least one of the latex foam rubber components of the padding elements, expands to distribute—with the aid of other components of the rubber padding—over a substantial area of the player's head the remainder of the shock energy of the blow under consideration.

The differing rates and degrees of distortion, under any given blow, of the shell 10, and the latex foam rubber components of the padding, and the gas-entrapping soft rubber components of that padding, and the differing rates at which such elements recover from their respective distortions, seem to be important in the accomplishment of the new kind of head protection which is afforded by our structurally new helmet.

Our new helmet is capable of being manufactured and being maintained in serviceable condition and repaired with reasonable ease and economy.

If one or each of the rubber components of the composite padding element 14 initially is of somewhat excess thickness, a shell 10 of one basic size may be accommodated to any one of two or three or more different head sizes by paring an appropriate amount of excess thickness from one or both of such rubber components, before such padding element 14 is mounted in the shell 10, this being possible because snug fits of the helmet with the forehead and crown of the head and base of the skull of a wearer are considerably more important than are snug fits with the sides of his head. Moreover, the rubber components of the composite rubber padding elements 25-25, if they be initially of excess thickness, similarly are subject to paring, in the interest of head size determination, if desired.

The composite rubber padding elements of our new helmet are readily inspected, cleaned, ventilated, and repaired. The composite rubber padding element 14 may be substantially completely withdrawn from the shell 10, as depicted in Fig. 7, for any of these purposes, but it will snap back into snug engagement with the shell interior as soon as its intermediate portion is pushed back into the shell. Whenever the helmet happens to be equipped with a chin strap 37, the latter may be employed as indicated in Figs. 1, 2 and 3 to retain the composite padding element 14 in the position of Fig. 7, in which it is withdrawn from the shell, as when the helmet is being ventilated. Moreover, the upper portion of each of the composite rubber padding elements 25-25 may be forcibly moved away from the shell interior, and be turned back upon the lower portion of that padding element, for purposes of inspection, cleaning, ventilation or repair.

Having thus illustrated and described a presently preferred practical embodiment of our invention, what we claim as new and desire to secure by Letters Patent of the United States is:

1. A helmet comprising a one-piece shell conformed to receive a wearer's head and extend downwardly over his forehead and his jaws and the base of his skull, and padding for the interior of said shell, said padding consisting of three separate padding elements, one of said padding elements being elongated and extending in contiguity with the shell interior from the forehead edge to the skull base edge of the shell, and the other two of said padding elements lying on opposite sides of said elongated padding element and being disposed contiguous the inner surfaces of the lateral walls of the shell, the elongated padding element being secured to the shell only at the forehead edge and the skull base edge of the shell by means providing a flexible hinge connection at one end thereof, said elongated padding element comprising in its construction resilient material and being adapted, by virtue of its own resiliency and said flexible hinge connection, to be pulled from the shell without being disconnected therefrom and moving snugly against the interior of the shell when pressed back into the shell.

2. A head helmet comprising an outer shell shaped to extend from the lower part of the forehead over the top of the head to the base of the skull, a strap located within the shell and having its ends attached to the outside of the forehead end of the shell and to the inside of the skull-base end of the shell, the strap being elsewhere free of attachment to the shell, and padding attached to the side of the strap facing the interior of the shell and extending from the

strap end attached to the skull-base end to a region of the strap spaced from the strap end attached to the forehead end of the helmet, the padding being attached to the shell only through the strap.

3. A head helmet comprising an outer shell shaped to extend from the lower part of the forehead over the top of the head to the base of the skull and over the ears, and a composite U-shaped padding for the shell including a soft outer lamina having separated closed cells containing entrapped gas and a soft inner lamina having interconnected air cells.

4. A helmet comprising a one-piece outer shape defining shell, conformed to receive a wearer's head and extend downwardly over his forehead and his jaws and the base of his skull, and formed of a composition that is tough and flexible and resilient and substantially free from brittleness at temperatures as low as zero degrees F., and composite padding comprising a normally flat unitary elongated element extending in U shape along the interior of such shell from base edge to the forehead edge, such composite padding including a plurality of laminae of soft resilient, cellular material which distort in differing degrees and at differing rates in transmitting with relative slowness, to and over substantial areas of the head of the wearer, the shock energy, not absorbed by the helmet, of blows which momentarily distort the shell and compress the laminae of the composite padding between the shell and the head of the wearer, at least one of the laminae of the composite padding being of a material having interconnected cells, and at least one other of such laminae being of a material containing a multiplicity of closed cells containing entrapped gas.

5. A helmet comprising a one-piece outer shape defining shell, conformed to receive a wearer's head and extending downwardly over his forehead and his jaws and the base of his skull, a composite padding lining the interior of such shell and extending in U shape along the shell, such composite padding including a plurality of different laminae of soft resilient, cellular material which distort in differing degrees and at different rates, in transmitting with relative slowness, to and over substantial areas of the head of the wearer, the shock energy, not absorbed by the laminae, of blows which compress the laminae of the composite padding between the shell and the head of the wearer, one of the laminae of the composite padding being of a material having interconnected air cells, and at least one other of said laminae being of a material in which gas is entrapped in separated cells.
